US00D887271S

(12) **United States Design Patent** (10) **Patent No.:** **US D887,271 S**
Hu et al. (45) **Date of Patent:** **** Jun. 16, 2020**

(54) **BOTTLE**

(71) Applicant: **PepsiCo, Inc.**, Purchase, NY (US)

(72) Inventors: **Simon Hu**, Qiqihar (CN); **Antonio Pugliese**, Milan (IT); **Gianmauro Vella**, Shanghai (CN)

(73) Assignee: **PepsiCo, Inc.**, Purchase, NY (US)

(**) Term: **15 Years**

(21) Appl. No.: **29/633,031**

(22) Filed: **Jan. 11, 2018**

(51) LOC (12) Cl. **09-01**

(52) U.S. Cl.

USPC **D9/500**

Goldstein & Fox, P.L.L.C.

(57) **CLAIM**

The ornamental design for a bottle, as shown and described.

DESCRIPTION

FIG. 1 is a top perspective view of a bottle showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the bottle that form no part of the claimed design.

The dot-dash broken lines in the figures show boundaries that form no part of the claimed design.

The appearance of the material from which the bottle is made forms no part of the claimed design.

1 Claim, 7 Drawing Sheets
